LADY'S STOCKING OR SIMILAR ARTICLE

Irving Belaief, New York, N. Y., assignor to Dainty Maid Hosiery Co., Inc., New York, N. Y., a corporation of New York

Application April 14, 1950, Serial No. 9,211

Term of patent 7 years

(Cl. D47—7)

To all whom it may concern:

Be it known that I, Irving Belaief, a citizen of the United States and a resident of Bronx County, New York city, N. Y., have invented a new, original, and ornamental Design for a Lady's Stocking, or Similar Article, of which the following is a specification, reference being had to the accompanying drawing, forming a part hereof, in which the figure is a side elevational view showing my new design for a lady's stocking or similar article. The essential features of the design reside in the portions shown in full lines on the drawing. The design of the present invention is characterized by a relatively high heel reinforcement which has substantially straight, elongated sides angled upwardly towards each other at the top of the reinforcement, the sides angling outwardly from the bottom a short distance, and then extending in a very shallow curve toward the tip of the foot, thence in a straight line forwardly and across the toe, the entire reinforcing portion except at the toe portion outlined by a shadow line which follows the contours of the body, all as shown.

I claim:

The ornamental design for a lady's stocking, or similar article, as shown and described.

IRVING BELAIEF.
